UNITED STATES PATENT OFFICE.

LEWIS J. LEDBETTER, OF McALLEN, TEXAS.

HAT-BOX.

1,186,920.

Specification of Letters Patent.

Patented June 13, 1916.

Application filed March 5, 1915. Serial No. 12,340.

To all whom it may concern:

Be it known that I, LEWIS J. LEDBETTER, a citizen of the United States; residing at McAllen, in the county of Hildago and State of Texas, have invented certain new and useful Improvements in Hat-Boxes; and I do hereby declare the following to be a full, clear, and exact description of the invention, such as will enable others skilled in the art to which it appertains to make and use the same.

This invention relates to new and useful improvements in hat boxes, and has for its principal object to provide a hat box which is capable of being used on shelves and upon which it is possible to pile additional objects and yet permit the user to remove a hat therefrom.

Another object of the invention is to provide a hat box having a removable cover as well as a hinged front wall in order that the same may be used on shelves and the like.

A further object of the invention is to provide a hat box which is constructed so as to effectively protect a hat against being crushed.

With these and other objects in view, the invention consists in the novel combination and arrangement of parts which will be fully set forth in the following specification and accompanying drawings, in which,

Figure 1 is a perspective view of a hat box constructed in accordance with this invention showing the door open, and Fig. 2 is a transverse sectional view through the center thereof.

Referring to the drawings by characters of reference, the numeral 1 designates as an entirety the body of the box comprising the bottom 2, having formed at the lateral edges thereof the side walls 3. A rear wall 4 is formed at the rear edge of the bottom 2 opposite the front wall 5 which is formed with the opening 6 through which a hat may be removed or replaced when so desired. The opening 6 extends entirely to the bottom of the box, but at the top and sides is separated by the solid portion of the wall as clearly illustrated in Fig. 1. It will thus be seen that the opening may be formed in the front wall of the box without weakening the same as the side walls will be held against bending movement and reinforced throughout its entire height.

Hingedly secured to the bottom of the box by means of the suitable strip of flexible material 7, such as cloth or the like, is the front door 8 which is as wide as the box and is high enough to cover the opening 5 so that the contents of the box will be protected. A suitable cover 9 of paper or a similar material overlies the hinge 7 and protects the same as clearly illustrated in Fig. 2.

In order to hold the front wall in a closed position shown in the drawing, a suitable flexible member 10, which is preferably a cord or string, is secured near the upper edge of said door by means of a strip of paper or similar material 11 which is glued or otherwise secured to the door. A similar strip of paper 12 overlies the flexible member 13 which co-operates with the member 10 in holding the door against the wall.

The cover of the box, which is designated generally by the numeral 14, comprises the body 15 having formed on its edges the downturned flanges 16 which partially overlie the front, rear, and side walls of the box to form a dust-proof joint which will effectively protect the contents of the box.

It will be apparent from the foregoing that in use the box may be placed on a shelf and articles piled on the top thereof and when so desired the flexible members 10 and 13 may be untied and the front door 8 will swing downwardly on the hinge 7 into the horizontal position shown in Fig. 1, thus permitting the contents of the box to be removed. It will be apparent that the contents may be easily withdrawn from the box as there are no projections on the bottom to interfere with the smooth sliding of the articles therefrom, and it is also evident that the articles on the top of the box need not be removed in order to remove the hat.

While in the foregoing there has been shown and described the preferred embodiment of this invention, it is to be understood that such changes may be made in the combination and arrangement of parts as will fall within the spirit and scope of the invention as claimed.

What is claimed is:

A hat box of the class described comprising a bottom, side, front and rear walls, said front walls being provided with a rectangular opening, said opening extending entirely to the bottom of the box, a portion of the side and top of the front wall being left

to reinforce the same, a strip of flexible material being secured to the outer face of the bottom of said box, a door approximately as wide as the box and as high and having one edge thereof secured to said strip, a flexible tying element secured to the top portion of the front wall and coöperating with a tying element on the door for holding said door in

a closed position, and a cover closing the top of said box, substantially as set forth. 10

In testimony whereof I affix my signature in presence of two witnesses.

LEWIS J. LEDBETTER.
